UNITED STATES PATENT OFFICE.

ANDREW J. McCORMACK, OF ROCHESTER, NEW YORK, ASSIGNOR TO UNITED SHOE MACHINERY CORPORATION, OF PATERSON, NEW JERSEY, A CORPORATION OF NEW JERSEY.

SOLE-EDGE-TREATING MACHINE.

1,352,209.

Specification of Letters Patent. Patented Sept. 7, 1920.

Application filed November 2, 1918. Serial No. 260,819.

To all whom it may concern:

Be it known that I, ANDREW J. McCORMACK, a citizen of the United States, residing at Rochester, in the county of Monroe 5 and State of New York, have invented certain Improvements in Sole-Edge-Treating Machines, of which the following description, in connection with the accompanying drawings, is a specification, like reference 10 characters on the drawings indicating like parts in the several figures.

This invention relates to machines for finishing or ornamenting shoes. The invention is herein disclosed by way of example 15 as embodied in a machine designed for finishing the marginal surfaces of soles of shoes, such as the upper and edge surfaces of the sole margins of shoes of various types, the term "marginal surfaces of soles" 20 being used for convenience to designate generically either surfaces of a sole *per se*, or surfaces of a welt, a slip sole or the like superposed upon the sole proper, as is characteristic of various types of shoes.

25 The illustrated machine is especially designed to indent the upper marginal surface of a shoe sole or the stock, such as a welt or mock welt, superposed upon the shoe sole to form what are known as im- 30 pression or imitation stitches and to burnish the indentations so formed, and also to burnish the vertical edge of the sole, this operation being performed after the sole has been trimmed to final shape and being 35 termed in the trade "edge setting". It is to be understood, however, that the invention in various of its aspects is not restricted to embodiment in machines of the particular type shown.

40 In the use of a machine for indenting, sometimes also called "wheeling", the said upper marginal surface it is frequently necessary to change the wheels, as shoes of different styles come to the machine, the 45 wheels being manufactured in many styles of depth and spacing of teeth. It is the object of my invention to provide a mounting for an indenting tool which shall permit instant removal, interchange and replacement 50 without loss of adjustment relatively to other parts of the machine.

The several features of the invention, including certain novel arrangements and combinations of parts, will be described in

the following specification and pointed out 55 in the claims.

Figure 1 of the drawings is a side elevation of the head of a burnishing machine in which my invention has been incorporated in a preferred form;

Fig. 2 is an enlarged section on the line 2-2 of Fig. 1;

Fig. 3 is an enlarged section on the line 3-3 of Fig. 1;

Fig. 4 is an enlarged detail showing the 65 operative surfaces of the tools in relation to the sole edge;

Fig. 5 is a detail view of the blank edge setting iron;

Fig. 6 is a section on the line 6-6 showing the iron adjustment;

Fig. 7 is a perspective of the head of the machine.

The machine has operating heads of two types, and is a twin machine having four 75 heads, altogether. The head 1 is mounted on the arm 2 which is caused to oscillate by any suitable mechanism not shown, driven by the pulley 6. This head carries two edge setting tools 3, 4 for forepart and shank, 80 respectively, and these tools are interchangeable by means of the handle 5, in well-known manner. The head 10 is mounted on the arm 12, which is likewise caused to oscillate by the mechanism of the machine. 85

The arm 12 has an arcuate slot 13 formed in one side in which slides a corresponding arcuate boss 14 formed on the inner surface of one of two spaced plates 15. The plates 15 have rack teeth 16 at their rear ends arranged on an arc of a circle concentric with the arcuate boss 14. Side plates 17 are bolted to the head 12 outside the plates 15 by transverse bolts 18 extending through them and the head 12. A pinion 19 mounted in 95 the plates 17, meshes with the rack teeth 16 and is operated by the knurled head 20. The bolt 18 passes through the plates 17 and an arcuate slot 21 in the plates 15 which are rigidly connected together in any suitable 100 manner as by a rib 15', and may be rotated about the center of curvature of the rack 16 by turning the knurled head 20. As will be shown later, this center is substantially 105 in the intersection of the working faces of the indenting wheel and the burnishing iron.

In the spaces between the edges of the plates 15 which project beyond the edges of

the head 12 are mounted the stitch indenting wheel carrier 22 and the iron 23. The carrier 22 is slidably mounted against the rib 15' between the plates 15 and has mounted upon it a spindle 24 which extends through the hole in an adjustable nipple 25 mounted upon the top edges of the structure 15-15'. The nipple is exteriorly threaded for adjustment in said structure and has a smooth passage for the spindle 24. The lock nut 26 holds the nipple in adjusted position. The carrier 22 is urged downward longitudinally between the plates 15 by a spring 27, one end of which rests against the carrier 15 and the other against the nipple 25. The carrier has a notch 28 in which a tooth 29 on a spring 30 is adapted to engage when the spindle 24 is drawn up to its utmost extent, thus holding the carrier 22 and the switch indenting wheel 31 retracted out of operative position when it is desired to dispense with it or to remove the iron 23 as will be described.

In accordance with the illustrated embodiment of the present invention, the stitch-indenting wheel 31 is held in the machine for ready removal and replacement by a toggle lever 27' at the upper end of the spindle 24, which turns down and is pulled against the nipple 25 by the spring 27. The whole carrier 22 may be removed by straightening the lever 27' as shown in dotted lines in Fig. 1, when the lever will slip through the nipple and the wheel carrier 22 can be removed. It is obvious that no loss of adjustment is involved in the removal and replacement of the carrier, as the adjusting parts, such as the nipple and its lock nut, are all mounted on the head 12 and are not moved in the removal of the carrier.

The iron 23 is rectangular in cross section and fits closely into the rectangular space between the square lower edge of the head 12 and the lower projecting edges of the plates 15. It is thus firmly supported against lateral vibration and against the tendency to rotate about its longitudinal axis. It is supported against longitudinal thrust by a rod or plunger 32' slidably mounted in bosses 33 and 38 on the head 12. This rod carries a pinned collar 34 between which and the boss 33 is mounted a spring 35 which holds the collar against the boss 38. A spring 32 mounted on the boss 33 engages a wedge surface 33', holding the iron firmly against the head 12 and the rod 32'. Pressure upon the projecting rear end of the rod 32' through the lever 27' will drive it forward against the spring 35 and cause it to knock the iron 23 forward past the spring 32, and out of the machine, the wheel 31 being previously drawn back out of the way as above described. It is clear that a hot iron can be removed quickly but without the necessity of touching it with the fingers, thus

avoiding injury to the operator and permitting a tighter, firmer mounting of the iron than has been heretofore used in this type of machine. A new iron may be inserted by placing it between the projecting edges of the plates 15 and pushing it backward until the spring 32 seats in the notch 33'. 70

The collar 34 rests against a knurled sleeve 36 on the rod 32', which has an externally threaded portion 37 screwing into the boss 38. The knurls are engaged by a spring-pressed locking plunger 39 in the head 12. A longitudinal adjustment of the iron 23 relative to the wheel 31 is thus permitted. 75

The center of curvature of the rack 16 and the boss 14 is substantially at the intersection of the wheel 31 with the working face of the iron 23. When the knurled head 20 is rotated the plates 15 carrying the stitch-indenting wheel 31 are rotated around this center so that the angle between the operative surfaces of the wheel 31 and the iron 23 is suitably changed without altering the registration of these tools relative to the work. 80 90

The iron 23 is not mounted upon the plates 15 but rests against the lower surface of the head 12 and remains immovable while the above-mentioned adjustment is made. It will be noticed that the operative (the 95 lower) surface of the wheel 31 is substantially parallel to the axis of the carrier 22, the journal of the wheel being set up at an angle, so that the operative surface of the wheel 31 will remain in contact with the 100 work in whatever position the carrier may take in sliding along the rib 15'. It will be obvious that the adjustment of the wheel 31 by means of the nipple 25 merely sets an outside limit to the protrusion of the carrier 22 from the plates 15. Pressure upon the outside surface of the wheel 31 will force it backward against the spring 27 so that it may respond to variations in the width of the upper surface of the sole edge, thereby 110 allowing the sole edge to rest firmly against the iron 23 while the outside surface of the wheel 31 rests against the lower edge of the vamp. Any desired means may be arranged to heat the iron 23 and wheel 31. 115

In the illustrated embodiments of the invention, I have shown two irons. The one shown in Figs. 1, 3 and 5 is adjustable in length by means of a screw 40, which connects its two parts 43, 44, and has a blank 120 end 42. The iron 23' shown in Fig. 4 has an edge setting surface at 46. In Fig. 1 the machine is shown as performing a simple wheeling operation, the iron 23 acting only as an abutment to support the sole edge 125 against the pressure of the wheel. The edge setting may be done upon the head 1 when the wheeling is done in this manner.

If desired, the wheeling and edge setting may be done in one operation as shown in 130

Fig. 4, the bevel and back at 48 supplying an abutment to support the shoe against the pressure of the wheel.

Having explained the nature of the invention and described a successful embodiment thereof, I claim as new and desire to secure by Letters Patent of the United States:—

1. In a machine for treating the edge and top marginal faces of a shoe sole, the combination with the edge and top tools and a holder therefor, and means for fixing the adjustment of one tool in the holder with relation to the other tool, of means detachably connecting the adjustable tool with the adjustment determining means and permitting the tool to be removed and replaced without disturbing the adjustment.

2. In a wheeling machine, the combination with means for resting a sole during treatment of its top marginal face, of a wheeling tool and a holder in which the tool is adjustable relatively to the resting means, and a connection between the holder and the tool including parts for effecting the adjustment and which are constructed and arranged to permit the tool to be removed and replaced while maintaining the adjustment of the adjusting part.

3. In a wheeling machine, the combination of a wheeling tool and a holder in which the tool is adjustable, and a connection between the holder and the tool including a spindle associated with the tool, a nipple adjustable in the machine longitudinally of the spindle and having an opening through which the spindle is removable, and means for normally retaining the spindle in predetermined longitudinal relation to the nipple and adapted to permit the withdrawal of the spindle and the tool and to secure them in the same relation to the nipple upon the return of the spindle to the nipple.

4. In a wheeling machine for indenting boot and shoe soles, the combination with an indenting tool and its support, of an adjusting and detachable connection between the tool and support constructed and arranged to assure the retention of the adjustment when the tool is removed and replaced,

an edge setting tool associated with the indenting tool, and means for securing the indenting tool support in different angular positions to vary the position of the tool relative to the face of the stock.

55

5. In a machine of the class described, an edge setting tool and an indenting tool arranged for relative adjustment and to cooperate in treating the marginal surfaces of a sole, each of said tools being constructed and arranged to be removed and replaced without loss of coöperative adjustment.

60

6. In a machine of the class described, a head having a channel, a tool carrier arranged for adjustment along the channel, and means for limiting the movement of the carrier along the channel comprising an abutment on the head and a member on the carrier in fixed relation to the tool carried thereby and arranged to contact with the abutment.

65

7. In a machine of the class described, a head having a channel, a tool carrier arranged for adjustment along the channel, and means for limiting the movement of the carrier along the channel comprising an adjustable abutment on the head and member on the carrier in fixed relation to the tool carried thereby and arranged to contact with the abutment.

75

8. In a machine of the class described, a head having a groove, a tool carrier arranged to slide along the groove, and a cross-piece on the carrier in fixed relation to the tool carried by the carrier, said cross-piece being arranged to lie across the end of the groove and to limit the movement of the carrier along the groove in one direction.

80

9. In a machine of the class described, a head having a groove, a member adjustably mounted in a direction parallel to the length of the groove, and a cross-piece on the carrier in fixed relation to the tool carried by the carrier and arranged to contact with the member to limit the movement of the carrier in one direction.

85

In testimony whereof I have signed my name to this specification.

ANDREW J. McCORMACK.
